DESIGN FOR A BEAD OR SIMILAR ARTICLE

Margaret H. Tang, New York, N. Y.

Application May 4, 1940, Serial No. 92,157

Term of patent 3½ years

To all whom it may concern:

Be it known that I, Margaret H. Tang, a citizen of the United States of America, residing in New York city, in the Borough of Manhattan, county and State of New York, have invented a new, original, and ornamental Design for a Bead or Similar Article, of which the following is a specification, reference being had to the accompanying drawing, forming part thereof, wherein,

I claim:

The ornamental design for a bead or similar article, substantially as shown.

MARGARET H. TANG.
